(57) **CLAIM**

The ornamental design for a hoop propelling toy, as shown and described.

DESCRIPTION

FIG. 1 is a perspective view of a hoop propelling toy showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view showing the toy in use.

The portions shown in broken lines in FIGS. 1 through 8 are for information only and form no part of the claimed design. The design is shown partially broken away in FIGS. 2-7 for ease of illustration.

1 Claim, 5 Drawing Sheets
